UNITED STATES PATENT OFFICE.

SOLON M. LANGWORTHY, OF CEDAR RAPIDS, IOWA.

AUTOMATIC VAPORIZER.

1,278,946.

Specification of Letters Patent. Patented Sept. 17, 1918.

Application filed January 5, 1917. Serial No. 140,830.

To all whom it may concern:

Be it known that I, SOLON M. LANGWORTHY, a citizen of the United States, residing at Cedar Rapids, in the county of Linn and State of Iowa, have invented certain new and useful Improvements in Automatic Vaporizers; and I do hereby declare the following to be a full, clear, and exact description of the invention, such as will enable others skilled in the art to which it appertains to make and use the same.

This invention relates to the production of combustible or explosive mixtures suitable for internal combustion or explosion engines, and has for its object the generation of such mixtures by the use of mechanism specially adapted for the purpose.

The invention consists in means for producing a mixture as aforesaid, by forcing air through a body of liquid suitable for the purpose, such as the various hydro-carbons, the air in its passage through the liquid gathering up sufficient thereof to render the product highly combustible or explosive.

The invention consists further in means for tempering or diluting the mixture so produced, which is ordinarily too rich in the liquid ingredient, by a superadded commingling therewith of air, preferably humid, or other ingredients.

These and other objects incidental to the invention are attained by mechanism hereinafter fully set forth, and clearly illustrated in the accompanying drawing, in which:

Figure 1 is a side view of mechanism adapted for the production of such an explosive mixture automatically and continuously by an automobile for the use of its engine. Fig. 2 is a longitudinal section of the initial mixture producer. Fig. 3 is a central, vertical section, of an auxiliary mixer and means for controlling the admission of the mixture into the explosion chamber of the engine. Fig. 4 is a section of a part thereof, to the right of the line A⁴—A⁴. Fig. 5 is a section of a very simple type of mixer shown as a primer only.

The principle of the invention is best illustrated in Fig. 5, the mechanism being very simple. The numeral 1 denotes the intake manifold of an engine (Fig. 1). To this is attached, as by a nipple 2 a receptacle 3 adapted to hold a quantity of a suitable vaporizable liquid, such as gasoline,

alcohol, or other hydro-carbon. The receptacle has an outlet 4, preferably leading downwardly, since the product of vaporization is heavier than air, and it is desirable to take advantage of gravity in delivering it where desired. An inlet 5 provides for the admission of air, the inner end of this inlet being below the upper end of the outlet, and preferably near the bottom of the receptacle. Suction being applied to the outlet, it will be evident that air drawn through the liquid will be more or less saturated therewith, according to the intensity of the suction, or the depth of the liquid, which is supposed to be kept always somewhat higher in the receptacle than the lower end of the inlet. The upward extension of the receptacle at 6 makes an air chamber, which prevents overfilling and flooding through the outlet. A cap 7 closes the top of the inlet, which has air-holes 8 to allow the inflow of air, the cap in this case being useful mainly the better to exclude dirt. This simple device is well adapted for use as a primer, for starting the engine, but for continuous service other mechanism is provided, which will now be described.

Referring to Fig. 1, the numeral 9 denotes one of the side sills supporting the engine, which is of a familiar type. In front of the engine is the usual radiator 10, connected with the water passages of the engine by tubes 11 and 12. Through the tubular steering-post 13 extends the throttle shaft 14 co-operating with bevel gears 15 to control the flow of explosive vapor, as will be described presently. The hood 16 and dash 17 may be as usually constructed. At some convenient place, here shown as adjacent to the engine and in front of the dash, is mounted a tank 18. If set where there is sufficient room this may be the main fuel supply tank, now usually placed at the rear of the automobile body (not shown), and preferably at a level lower than the intake manifold. As illustrated, the tank may be considered as an auxiliary to such a main supply tank, which should set a little higher, and taking its contents through a pipe 19. In any case, the tank 18 is in practice made of generous size, so as to deliver a volume of vapor in excess of all possible requirements of the engine. It is preferably of large area, and comparatively shallow, so that changes in the depth of liquid are

never very great. Entering the tank from above is a tube 20, which extends to near the bottom of the tank. The upper end should be capped at 21, to shield the tube 5 from dust or rain, and is pierced at 22 for the admission of air. A cork tell-tale 23 serves to prevent overfilling. Surrounding this inlet tube is a float 24 having a chamber 25 formed therein, the upper part of said 10 chamber serving as a guide for the float. An outlet is provided at 26, and connecting with this outlet is a flexible tube 27, as of rubber leading to the service pipe 28. The flexible tube allows the float to move freely up and 15 down and tilt sidewise or endwise as the position of the tank shifts over an unlevel road. The service pipe leads to a connection (mediate as herein shown) with the intake manifold of the engine, and is therefore 20 subjected to the suction of the engine pistons. It will be evident that this suction would draw from the tank saturated air if the float and flexible tube were dispensed with, but the construction shown is useful, 25 nevertheless, in a number of particulars. One important function the float performs is to largely prevent splash in the tank. It also serves in a measure to equalize the 30 withdrawal quality of the mixture, since the withdrawal thereof is always from the same point as regards the surface of the liquid. This is important when the vapor is drawn from a large tank, as in this case, since otherwise 35 its richness might vary in different parts of the tank. The advantage which the construction supplies, in the matter of simplicity, and in dispensing with a delicate float valve, liable to clog or leak, will be evident. It also takes advantage of the 40 greatest agitation and aerification of the liquid, which is of course just around the lower end of the inlet. In practice this construction would serve the engine with an abundant supply of vapor, but too rich if 45 gasoline at ordinary temperatures is used. Provision is made, however, for still further enriching the mixture. This consists of a pipe 29 leading from the liquid directly, and 50 preferably discharging through a jet 30 regulated by a needle valve 31. The adjustment of this needle valve will be described presently.

Instead of connecting the service pipe 55 directly with the intake manifold, it is in practice preferred to interpose a mixing chamber 32, best made funnel shape, substantially as shown, giving a constricted outlet at 33, whence it flares downwardly. In the mouth of the outlet is fitted a check- 60 valve, here shown as a ball 34, seated by a light spring 35, which arrests any backward movement of gas or other products of combustion. The spring may be supported on a gauze screen 36, which serves as a strainer, 65 and also arrests back-firing. In the service

passage is mounted a butterfly valve 37. Another valve 38^a is seated in the elbow 38 connecting the mixer with the manifold. The cranks of these valves connect by a link 39. Another link 40 connects the lower 70 crank with the crank 41 of one of the throttle gears, and thus by the turning of the throttle-shaft the valves are actuated in unison. Concurrent action of the needle-valve, when such action is required, is effected by a 75 lever 42 and a link 43 connecting it with a lever 44 on the needle. The action of this lever 42 may be adjusted, or neutralized altogether, by passing the link stem through the lever wrist 45 loosely, and providing it 80 with collars 46 adjustable to any desired point on the stem. Unless the hydro-carbon be of low grade this jet of raw liquid is seldom needed. It is to be noted, however, 85 that it does not enter the explosion chamber of the engine as a raw liquid, but commingled and diluted with air.

As above suggested, the main service pipe is ordinarily sufficient, and much more than sufficient for the requirements of the engine, 90 with an abundant supply of rich vapor. It is now only necessary to reduce it by an admixture of air, or air commingled with other ingredients, one of the most efficient of which is water. The device for this purpose is in the main a duplicate of that shown in Fig. 5, consisting of a receptacle 47 with a depending inlet 48, and an upstanding outlet 49 arranged as already described. The outlet is best provided with a check-valve 50, 100 of a simple type, requiring no description. The inlet is shown provided with a cap 51, which may be removed to admit dry air. It is also shown piped to the upper part of the radiator by a pipe 52. A shut-off valve 53 105 may be opened or closed by a rod 54 passing through the dash. It is also shown piped to the water in the radiator, by pipe 55, also provided with a shut-off valve. Preferably, but not necessarily, the air admitted through 110 the inlet 48 is made to pass through a body of water, and thus reaches the mixing chamber below in a humid condition. The same would take place if the humid air from the upper part of the radiator were passed directly to such mixing chamber, as would be 115 the case if there were no water in the receptacle.

The mechanism above described is adapted to produce an inexhaustible supply of the 120 explosive vapor, and this may be easily diluted to the proper point of highest efficiency without the use of minute valves and other delicate mechanism.

It is adapted to secure a very pure product, free from dust and other ingredients detrimental to the engine and its working, a large proportion of the carbon deposit in explosion chambers being road dust. This is rendered possible by the fact that before 130

the explosive vapor reaches the point in its course where any delicacy of adjustment is required it has been thoroughly washed and freed from particles of solid matter.

5 The device admits of the whole supply of liquid being placed at a lower level than the intake manifold, thus dispensing with the need of employing either gravity or vacuum to produce a flow of the liquid. This 10 also eliminates the inconvenience and danger due to flooding.

As the device in vaporization deals with a large mass it is well adapted to produce explosive mixtures in practical working 15 volumes from low-grade hydro-carbons.

The fact is recognized that in time more or less foreign matter will accumulate in the bottom of the float-tank. It is accordingly provided with a settling well 56 and drain 20 cock 57, so that the impure residuum may be drawn off and filtered or thrown away.

In Fig. 2 is shown a screen 58 across the tube 20, for the purpose of breaking up air-bubbles, thus securing a better saturation of 25 the indrawn air.

The cap may be made adjustable on the upper end of the tube 20, as by threading, and thus serve to close or open the air-holes more or less. This will of course increase 30 or diminish the relative work of the air-supplying auxiliary 47, and thus automatically temper the mixture by very simple means.

It will be evident that an increase in suction will correspondingly increase the supply of both air and liquid, and vice versa, the process being thus exactly adapted to the requirements of a motor running at varying 35 speeds.

40 Having thus described my invention, I claim:

1. Combined with the intake manifold of an internal explosion engine, a vaporizer 45 adapted to supply an explosive mixture to said manifold, and also to supply the same with undiluted liquid, a pipe for said vapor opening into the upper part of said manifold, a separate pipe for said liquid, and means to control the admission of both vapor 50 and liquid.

2. Combined with the intake manifold of a gasoline engine, a vaporizer adapted to

supply an explosive mixture to said manifold, vapor-modifying device mounted above the manifold, and communicating therewith, comprising a receptacle adapted 55 to hold liquid, an air inlet tube extending to near the bottom thereof, an outlet opening inwardly above the surface of said liquid and at its lower end into the manifold, a 60 pipe connecting the vaporizer with the vapor modifier, and a check-valve adapted to prevent back-firing into said modifier.

3. Combined with the intake manifold of an internal explosion engine, a vaporizer 65 adapted to supply an explosive mixture to said manifold, and also to supply the same with undiluted liquid, a pipe for said vapor, a throttle-valve therein, a separate pipe for said liquid, a valve therefor, and means 70 adapted to operate said valves concurrently.

4. Combined with a vaporizer adapted to supply an explosive mixture to the intake of a gasoline engine, a vapor modifier, comprising a receptacle adapted to hold liquid, 75 an inlet tube therein extending to near the bottom of the receptacle and communicating with said vaporizer, an outlet extending inwardly above the surface of the liquid, and outwardly communicating with the intake, a pipe leading from the upper part of 80 said receptacle to a source of moisture, as the radiator of the engine, a valve therein, and a rod accessible to the operator of the engine, and adapted to open and close said 85 valve.

5. Combined with a vaporizer adapted to supply an explosive mixture to gasoline engines, an auxiliary vapor-modifying device mounted above the intake of the engine, and 90 communicating with the vaporizer, a check-valve therein, a throttling device attached to the engine manifold, and supporting the modifier, said throttling device having a 95 passageway for vapor flared above and below a constricted neck, and provided with a check-valve and throttle-valve substantially as set forth.

In testimony whereof I affix my signature in presence of two witnesses.

SOLON M. LANGWORTHY.
